INVENTOR,

Arthur J. Choquet

UNITED STATES PATENT OFFICE.

ARTHUR J. CHOQUET, OF NEW YORK, N. Y., ASSIGNOR, BY MESNE ASSIGNMENTS, TO ADOLPH M. DEUTSCH, OF COUNTY OF QUEENS, NEW YORK.

NECKBAND-FASTENING MEANS FOR COLLARS.

1,379,527.

Specification of Letters Patent.

Patented May 24, 1921.

Application filed January 10, 1920. Serial No. 350,518.

To all whom it may concern:

Be it known that I, ARTHUR J. CHOQUET, a subject of the King of England, residing at New York city, borough of Manhattan, 5 in the county and State of New York, have invented certain new and useful Improvements in Neckband-Fastening Means for Collars, of which the following is a specification.

- 10 The present invention relates to improvements in neckbands forming part of shirts, shirtwaists and the like, the object being the elimination of independent loose means to the back of the band for holding the collar.
- 15 Another object of my invention is the fixity of the parts held together at all times. Due to the particular construction of my attachment and the manner in which it is fixed to the band, there is no friction 20 between the fastener and the band, as is experienced with the common stud or other attachment.

Furthermore, my invention completely eliminates the possibility of the collar swaying either sidewise or up and down or, even 25 forcing itself out of its anchorage as it happens sometimes when the stud or other attachment passes out of the button hole.

A further object of my invention is in 30 the manner of attaching its fastening means, whereby the different parts form a complete unit that can go through the process of laundering, without varying from the common practice in washing, starching and 35 ironing, the neckband at all times having a smooth surface except for a slight ridge where the plate is fastened.

My invention has also for its object provisions which permit a collar, of turndown 40 style, to fit snugly on the back of the neck without pressure at the fastening point as is commonly experienced with studs. Also, in the makes of certain collars claiming 45 that their particular construction allows an easy motion of the tie between its folds, my invention is so constructed that it helps that particular claim instead of impairing its function.

Other objects and advantages of my invention will become manifest in the detailed description which will follow, accompanied 50 by illustrations to which are applied similar reference characters representing similar parts throughout the different views.

- 55 Figure 1, is a perspective view of the up-

per part of a shirt showing the neckband thereof with my fastening means attached thereto.

Fig. 2, is a perspective of the fastener itself, showing its particular construction. 60

Fig. 3, is a view showing the manner in which the fastener is attached to the band.

Fig. 4, is an enlarged vertical section taken on line 4—4 of Fig. 3, with the collar 65 in position.

Fig. 5, is a horizontal section, also enlarged, taken on line 5—5 of Fig. 3, also showing the collar in position.

Referring now in detail to the different views, A shows the upper portion of a shirt 70 to which is fastened, in the ordinary manner, a neckband B to the back of which is attached a fastener C serving to hold a collar D.

Ordinarily the neckband B is made of two 75 or more layers of fabric the lower edges of which are turned inwardly and sewn to the shirt A as at 6. At the central rear portion of the shirt, the outer layer 10 of the neckband B is cut away at 7 to form a square 80 comparatively less in width than the distance between the edges 8 and 9 of the fastener C, as is shown in Fig. 3. The distance from the edge 11 of the inner seam, at the upper part of the neckband B, to the 85 upper edge 12 of the cut away portion, is slightly greater than the width between the edges 13 and 14 of the fastener C. The legs 15 of the fastener C are slightly short of the lower seam 6 of the neckband B. It 90 will be obvious, in referring to Fig. 3, that the fastener C abutting against the inner seam 11, is held firmly in position, between the layers of the neckband B, by sewing the edges of the cut away portion closely around 95 the edges 8, 9 and 14 of the fastener C.

Around the edges 8, 9 and 14, and the lower edges of the legs 15, I preferably sew with a double stitching, so as to form a slightly higher ridge offering thereby full 100 protection to the center lug 16, which is bent outwardly at 17, slightly below the edge 14, to allow easy and close fitting of the collar D as shown in Fig. 4. The portion 18, below the button hole of the collar D, is 105 forced toward the neckband into the cut away at 7, allowing a free space 19 all along in between the two folds of the collar D. Fig. 5 also clearly shows the inward pull of portion 18, of the collar D, into the 110

cut away at 7, showing the freedom of the space 19.

In cutting the material away at 7, to form the ridge protecting the raised lug 16 of the fastener C, I may take away that portion entirely and stitch the edges heavily, as aforesaid, or I may fold the material over as shown at 20, in Fig. 5, thereby offering ample protection to the raised lug 16. While 10 washing the shirt A, no common element can injure the fastener C or be injured thereby. It is in starching the neckband B that the construction of my invention offers the safeguard against any injury, which 15 has been so far found almost impractical. After applying the starch, it is a common practice to rub away the surplus amount, and if any sharp edges exist, unless fully protected, would undoubtedly be injurious 20 to the operator, but in this device the raised edges bordering the cutaway at 7 fully protect from injury. The raised lug 16, of the fastener C, is further protected by the raised edges of the cut away at 7, while the shirt 25 is passing through the last stage of laundrying, which is ironing, either by machinery or by hand; and it is obvious that the lug 16 cannot be flattened or distorted while protected by the thickness of the ridge bordering the cut away at 7. It is understood that 30 my fastener C is made of such metal as can be made absolutely rust-proof and as thin as is consistent with the required strength for the purpose.

35 While I have remodeled the neckband of old shirts, to show the feasibility of my invention, it will be of more practical value to adapt my fastener to a new standard in neckband, somewhat like the one I have 40 illustrated as example. The mere fact that

a shirt carries its own fastening means, for the back of the neckband, is of no small value, both commercially and practically.

In Fig. 2, I have shown a preferred form of construction of my fastener C which embodies the most convenient features of an attachment, yet I do not wish to be limited to that particular shape in its construction but I may make any change in its appearance as well as in the manner of fastening the same to the neckband; in fact arranging the same in any manner consistent with the scope and spirit of my invention.

What I claim is:

1. A device of the class described, comprising, in combination with a shirt band, of a metal plate secured in said band at the back thereof, said plate being bent to conform to the curvature of the band, and a raised, down-turned hook-like element 60 formed with said plate extending outwardly at the center of said band, adapted to engage in the rear buttonhole of a collar.

2. A device of the class described, comprising, in combination with a shirt band and collar, of a three pronged metal plate inserted and secured interiorly of said band, the center prong being offset outwardly and extended through the band at its center at the back and adapted to engage 70 in the button hole of said collar.

In witness whereof I have hereunto set my hand in the presence of two subscribing witnesses.

ARTHUR J. CHOQUET.

Witnesses:

ADOLPH M. DEUTSCH,
PAUL D. ELKIND.
